[57] **CLAIM**

The ornamental design for a foldable platform for supporting an ice fishing structure, as shown and described.

DESCRIPTION

FIG. 1 is a perspective view of a foldable platform for supporting an ice fishing structure showing my new design;

FIG. 2 is an enlarged top plan view thereof;

FIG. 3 is an enlarged side elevational view thereof, the opposite side being a mirror image of that shown;

FIG. 4 is an enlarged front elevational view thereof, the rear being a mirror image of that shown; and,

FIG. 5 is an enlarged bottom plan view thereof.

FIG. 2

FIG. 5
